UNITED STATES PATENT OFFICE

WILLIAM L. M. JONES, OF WINNIPEG, MANITOBA, CANADA

SHOCKER

Application filed February 14, 1927, Serial No. 168,222, and in Canada January 7, 1927.

The invention relates to improvements in shocking machines of the type in which a receiver for grain say, or the like, is moved rearwardly from a shock forming platform 3 and opened at its rear side for dumping the shocks as they are completed, such a machine being shown in Canadian Patents Nos. 192, 528 dated September the 9th, 1913; 235,215 dated the 7th day of August, 1923, and 235, 10 684 dated the 3rd of November, 1923. In such patented machines the receiver for the grain was moved rearwardly and subsequently forwardly by endless driven side chains and I have found that such a type of drive 15 is not dependable and an object of the present invention is to provide an improved and positive driving mechanism for the grain receiver, which is at all times under the control of the attendant and which is arranged so 20 that it automatically stops when the grain receiver has reached its limited forward or rearward position.

A further object of the invention is to provide means associated with one of the driving 25 pinions employed, which will engage with such driving pinion and hold it releasably locked after it has disengaged with the rack associated therewith, such insuring that the teeth of the pinion will subsequently mesh 30 with the rack teeth.

With the above more important objects in view the invention consists essentially in the arrangement and construction of parts hereinafter more particularly described, reference 35 being had to the accompanying drawings, in which:—

Fig. 1 is a side elevation of one side of the machine looking at it from the inner side, the rotatable platform which closes the bottom of 40 the grain receiver being shown in vertical section, such section being taken at 1—1' Figure 2.

Fig. 2 is a plan view of the central part of the shaker.

Fig. 3 is a vertical sectional view at 3—3' 45 Figure 2.

Fig. 4 is a vertical sectional view at 4—4' Figure 2.

Fig. 5 is a vertical sectional view at 5—5' 50 Figure 1.

Fig. 6 is a perspective view of the catches controlling the positions of the lever.

In the drawings above briefly described the numeral 1 designates the main wheeled frame of the machine including a pair of similar parallel vertical side frames 2. The numeral 55 3 designates the rotatable platform which normally closes the lower end of the upright cylindrical grain receiver 4, the grain receiver in such position receiving grain and the like 60 from an attached harvesting machine (not shown). The side frames aforesaid each comprise parallel upper, lower and intermediate beams 5, 6 and 7 which are suitably connected by uprights 8, and it will be here observed that the beam 7 stops rearwardly in a 65 location approximately opposite the rear edge of the platform 3, whilst the beams 5 and 6 project rearwardly considerably therebeyond and form upper and lower guide tracks 9 and 10, utilized to support two vertical and parallel carrier frames 11 and 12.

These carrier frames are substantially rectangular and are suitably braced, and each presents a horizontally disposed top bar 13, a horizontally disposed lever bar 14 and an intermediate horizontally disposed bar 15. These carrier frames are carried by suitably disposed rollers which operate on the tracks 70 9 and 10, the top bar 13 of the carrier frame 80 being herein shown as provided with two rollers 16 and 17 operated on the track 10 and the lower corners of such frame being provided with rollers 18 and 19 operating on the track 9.

The carrier frames support the grain receiver 4 which is positioned therebetween and suitably permanently attached to the carrier frames such as by fastening bars 20, the arrangement being such that the receiver can move from its normally forward filling position over the platform 7 rearwardly to its discharging position at the rear of the platform and then back to its initial position and whilst carried by the tracks.

The means employed for simultaneously and positively controlling the movement of the carrier frames forms for the greater part, the substance of the present invention.

I have hereinbefore mentioned that the 100

grain is delivered into the shock receiver from a harvesting machine and in so far as the present disclosure is concerned the harvesting machine frame is generally indicated by the reference numeral 21, the side next to the shocker being supported by a comparatively large bull or master wheel 22 as is common. The binder frame supports also a beam 23 parallel to and horizontally opposite the beam 7. The master wheel is fitted on the side next the shocker with a comparatively large internal driving gear wheel 24 suitably secured thereto in any well known manner so that such wheel will rotate at all times with the master wheel.

The beam 23 and the beam 7 at the inner side of the shocker support opposing bearings 25 and 26, which are secured permanently to the undersides thereof and receive rotatably a flanged sleeve 27 and a hub 28, the hub being integrally formed with a pinion 29 and a clutch member 30. A counter shaft 31 having one end circular in cross section and the other end square in cross section is provided, the circular end of the shaft being received rotatably within the hub 28, and the square end of the shaft being passed through a square hole provided in the sleeve 27 and having the protruding end thereof fitted with a pinion 32.

The pinion 32 meshes continuously with the internal gear 24 and the pinion 29 operates on the horizontally disposed rack bar 33, permanently secured to the underside of the intermediate bar 15 of the inner carrier frame. On the square end of the shaft 31 I mount slidably a shiftable clutch member 34 which is adapted to be brought into engagement with the clutch member 30 and such causes the shaft 31 to drive the pinion 29. The clutch member 34 is supplied with a peripheral channel 35 for a purpose later described.

The beam 23 and the adjacent beam 7 also support top bearings 36 and 37 which receive rotatably a sleeve 38 and a hub 39, the latter sleeve and the hub being constructed similar to the former and carrying a counter shaft 40 similar to that 31. A pinion 41 is formed integrally with the hub 39 as is also a clutch member 42, and the pinion is adapted to engage a rack bar 43 secured to the upper side of the inner bar 15 of the carrier frame. The end of the shaft 40 remote from the pinion 41 is provided with a pinion 44 which meshes continuously with the internal gear 24. A shiftable clutch member 45 is mounted on the square portion of the shaft 40 and is adapted when shifted into engagement with the clutch member 42 to cause the counter shaft to drive the pinion 41. The clutch member 45 is also supplied with a peripheral channel 46.

The harvester frame carries a controlling lever 47 pivotally attached thereto at 48, and to the lever above and below the pivot point I

pivots attach upper and lower operating bars 49 and 50, the operating bars extending towards the shocker and having the extending ends thereof pivotally connected to similar pivoted rocker bars 51, one of which is connected by a strap 52 to the clutch member 45, and the other by a strap 53 to the clutch member 34, the straps in both instances being received within the channels of the clutch members.

According to the above arrangement it will be apparent that when the upper end of the lever is swung say towards the harvesting machine, the clutch members of the counter shaft 40 will be engaged, whilst those on the counter shaft 31 will be passed away from one another and that a movement of the lever 47 in the opposite direction will engage the clutch members on the shaft 31 and disengage those of the shaft 40.

Means is provided for releasably locking the lever in neutral and in its shifted positions, such embodying spaced stops 54 and 55 permanently secured to an adjacent frame bar 56, the stops being herein shown in the form of angle brackets. When the lever is between the stops (see Fig. 6) the clutch members are in neutral position, that is, they are both disengaged. The attendant can release the lever from between the stops by pulling it backwardly to clear the stops and then setting it as he desires to the outer side of one stop or to the outer side of the other stop in which positions of the levers one or other of the clutches will be engaged.

The tracks 9 are provided each with a bearing 57 which supports rotatably a cross shaft 58, and the cross shaft is provided with pinions 59 and 60 which mesh with similar tracks 61 and 62 permanently secured to the undersides of the lower bars 14 of the carrier frames. The forward end of the rack bar 43 has a number of teeth thereof removed as best shown in Figure 1 and the rear end of the rack bar 33 has also a number of the teeth thereof removed and as appearing best in Figure 1. This arrangement is so that when the grain receiver is returning to its normal or forward position, the teeth of the then driving pinion 29 will clear or run off the teeth at the rear end of the rack bar 33, whilst the teeth of the then idling gear wheel 41 are still engaged with the teeth of the rack bar 43 and such that in the rearward movement of the receiver the teeth of the then driving gear wheel 41 will run off or clear from the teeth of the forward end of the rack bar 43, whilst the teeth of the then idling gear wheel 29 are still engaged with the teeth at the forward end of the rack bar 33.

The carrier frame next the full wheel is obviously driven by the pinions 32 and 44 and as the latter carrier frame moves in either direction it causes the rotation of the pinion 59 which in driving the shaft 58 positively

drives the pinion 60 and accordingly simultaneously shifts the other carrier frame in unison therewith. With this driving arrangement there is no possibility of the carrier frames getting out of alignment one with the other, and the drive is always positive in either direction and such was not obtainable with the type of chain drive shown in the patents hereinbefore mentioned.

As the pinions 41 and 29 are at all times directly under the control of the lever 47 as the grain receiver is moving backwardly or forwardly the attendant can stop the carrier by shifting the lever to the neutral position, and further on account of the structural arrangement it is unnecessary for the attendant to worry about the receiver when it reaches its foremost or rearmost positions, as the driving pinion automatically runs off the end of the rack which results in the stopping of the movement of the carrier frames until such time that the attendant shifts the lever to the reverse position, at which time the movement of the carrier frames will reverse.

I have provided means associated with the pinion 41 for releasably locking the pinion in a set position immediately it runs off the forward end of the rack bar 43, such insuring that when the rack bar is subsequently advanced under the driving action of the pinion 29, the teeth of the pinion 41 will go smoothly into mesh with the teeth of the rack bar 43. The means employed comprise a horizontally disposed bar 63 having one end pivotally attached at 64 to the adjacent carrier frame and the other end provided with a V-shaped catch 65 overlying the pinion 41. An upright arm 66 is attached to the latter carrier frame and carries a bracket 67 (see Figure 5) against which the bar 63 is resiliently held by the action of the coil spring 68.

It will be observed that when the pinion 41 runs off the forward end of the rack 43 it is engaged by the catch 65 of the bar 63, which will hold it subsequently against rotation and which insures that when the carrier frame is subsequently advanced the pinion 41 will pass smoothly into mesh with the teeth of the rack bar 43. Immediately following the intermeshing of the said pinion and teeth the bar 63 moves away from the said latter pinion, being carried forward with the carrier frame on which it is mounted.

Whilst I have shown a bar 63 as associated only with the pinion 41, I wish it to be understood that a similar bar could be used with the pinion 29 to releasably hold it in place after it has run off the rear end of the rack bar 33.

What I claim as my invention is:—

1. In a grain shocking machine in combination, a main frame presenting opposing, upstanding side frames, similar opposing up-

standing carrier frames carried by the side frames and rearwardly moveable thereon, a shock forming receiver carried by and moveable with the carrier frames, a pair of adjacent rack bars permanently secured to one of the carrier frames, selectively driven pinions carried by the main frame and engaging said rack bars, a further pair of rack bars secured to the carrier frames, a cross shaft carried by the main frame and pinions secured to the shaft and engaging the latter rack bars. 70

2. In a grain shocking machine in combination, a main frame presenting opposing, upstanding side frames, similar opposing upstanding carrier frames carried by the side frames and rearwardly moveable thereon, a shock forming receiver carried by and moveable with the carrier frames, a lengthwise extending rack bar secured to one of the carrier frames and having the teeth thereof extending upwardly, an adjacent lengthwise extending rack bar secured to the latter carrier frame and having the teeth thereof extending downwardly and selectively driven pinions carried by the main frame and engaging the rack bars. 85

3. In a grain shocking machine in combination, a main frame presenting opposing, upstanding side frames, similar opposing upstanding carrier frames carried by the side frames and rearwardly moveable thereon, a shock forming receiver carried by and moveable with the carrier frames, a lengthwise extending rack bar secured to one of the carrier frames and having the teeth thereof extending upwardly, an adjacent lengthwise extending rack bar secured to the latter carrier frame and having the teeth thereof extending downwardly, selectively driven pinions carried by the main frame and engaging the rack bars, 95 a further lengthwise extending rack bar permanently secured to each side frame, a cross shaft carried by the main frame and pinions secured to the cross shaft and engaging the teeth of the latter rack bars. 100

4. In a grain shocking machine in combination a main frame presenting opposing, upstanding side frames, similar opposing upstanding carrier frames carried by the side frames and rearwardly moveable thereon, a shock forming receiver carried by and moveable with the carrier frames, a lengthwise extending rack bar secured to one of the carrier frames and having the teeth thereof directed upwardly and the forward end thereof presenting an extending portion free of teeth, a lengthwise extending rack bar secured to the latter carrier frame and underlying the former rack bar and having the teeth thereof directed downwardly and the forward end thereof extending in advance of the forward end of the former rack bar and the lower end thereof terminating in advance of the rear end of the former rack bar and free of teeth, 115 a pair of counter shafts rotatably carried by 120 the latter carrier frame and underlying the former rack bar and having the teeth thereof directed downwardly and the forward end thereof terminating in advance of the rear end of the former rack bar and free of teeth, 125 a pair of counter shafts rotatably carried by 130 the latter carrier frame and underlying the former rack bar and having the teeth thereof directed downwardly and the forward end thereof terminating in advance of the rear end of the former rack bar and free of teeth,

the main frame, pinions secured to the counter shaft, means for continuously driving the pinions in the same direction, pinions rotatably mounted on the counter shafts and engageable with the respective rack bars, disengageable clutch members mounted on the counter shafts and controlling the driving of the latter pinions, means for selectively engaging the clutch members to selectively drive the latter pinions, a pair of lengthwise extending rack bars secured permanently to the carrier frames, a cross shaft rotatably carried by the main frame and pinions secured to the cross shaft and engaging the latter rack bars.

15 Signed at Winnipeg, this 2nd day of February, 1927.
